FESTOONING MACHINE

Ralph N. Moore, Manly, Iowa

Application July 15, 1947, Serial No. 761,055

5 Claims. (Cl. 57—4)

1

This invention relates to a festooning machine. It is an object of the present invention to provide a festooning machine which may be loaded with boughs or branches at a remote point from the winding element and on an arm which periodically can be brought upwardly with the boughs to locate them upon a member which retains them while being connected to a central wire by a wire which is wound about the boughs and wherein there is provided in the hand or device into which the boughs are placed an automatically operated lever which as the arm is brought over to locate the boughs on the wire will release the boughs for delivery to the winding holder or hands.

It is another object of the present invention to provide a festooning machine wherein there is associated with the driving parts a brake adapted to retain the parts against turning movement at all times except when released by the operator upon his stepping upon a foot treadle, the release of which will stop the winding holder and wherein such brake includes a wheel which is a part of the driving mechanism and rotates and wherein the brake surface is provided on a stationary part, the wheel being adjustable into and out of engagement with the stationary part and whereby to keep the number of parts within the machine to a minimum.

It is another object of the present invention to provide a simple mechanism for retaining in proper fashion the wire which is wound about the boughs upon the central wire and wherein this part can also serve as a countershaft to transmit power to other working parts of the machine and thereby in this manner keep the number of working parts on the machine to a minimum.

Other objects of the present invention are to provide a festooning machine with which a large output of festoon can be had with little effort, wherein such machine is of simple construction, inexpensive to manufacture and efficient in operation.

For other objects and for a better understanding of the invention, reference may be had to the following detailed description taken in connection with the accompanying drawing, in which

Fig. 1 is an end elevational view of my festooning machine looking upon the bough feeding arm and illustrating in dotted lines the manner in which it is extended to the holder about the wire.

Fig. 2 is a top plan view of my machine.

Fig. 3 is a side elevational view of my machine showing the brake operated lever extending there-

from and the wire coils from which both the central wire and the winding wire is extended.

Fig. 4 is an enlarged side elevational view of the winding wire holder with portions broken away and shown in section to show the interior thereof and the manner in which the wire is retained therein.

Fig. 5 is an enlarged fragmentary and cross-sectional view of a post device on the winding wire holder for retaining the wire externally of the holder and through which it is fed and kept tight by the same.

Fig. 6 is a fragmentary and cross-sectional view taken generally on line 6—6 of Fig. 2.

Referring now to the figures, 10 represents a bench-type frame having legs 11 and vertically spaced transversely extending frame portions 12, 13 and 14. The frame portion 12 is vertically adjustable in the legs 11 whereby a tightening of the driving chains or belts to be mentioned can be effected. Elongated slots 15 are provided in the legs 11 to permit the vertical adjustment of the frame portion 12 and screws 16 when tightened fix the frame portion to the legs 11 in the differently adjusted positions thereon.

On the frame portion 12 there is mounted an electric motor 17 having a multi-groove pulley 18 connected by a belt 19 to a pulley 21 on a countershaft 22, journaled on frame portions 13. On the shaft is a friction pinion 23 engaging with a wheel 24 to drive the same. This wheel 24 is fixed on a shaft 25 journaled in an adjustable and eccentric part 26 which is in turn supported in bearing blocks 27. An arm 28 extends from the eccentric 26 and can be adjusted to move the wheel 24 into engagement with the pulley pinion 23 on shaft 22 so that the wheel 24 will be driven. A spring 29 cooperates with the arm 28 to keep the eccentric 26 adjusted so that normally wheel 24 will be maintained in engagement with a stationary brake element 31, Fig. 6. Thus the wheel 24 is retained normally against rotation. To place the wheel 24 in engagement with the pinion 23, a foot treadle 32 pivoted to the bottom frame portion 12 as indicated at 33, is depressed. To this treadle there is connected a link 34, a spring 35 and a link 36 which are connected together in chain fashion and connected with the treadle 32 through the link 34. The upper end of the link 36 is connected to an arm 37 fixed to a shaft 38 and journaled in bearing brackets 39. At the opposite end of the shaft 38 is an arm 41 which is connected by a link 42 to the eccentric arm 28.

Accordingly as the treadle 32 is depressed, the wheel will be brought into engagement with the

pulley pinion 23. Upon release of the treadle, the wheel will be returned to the brake 31.

On the top portions 14 there is journalled in bearings 44 and 45 thereon a winding wire holder 46 having sprockets 47 and 48 thereon. Through this holder there is extended a central or large diameter wire 49 to which boughs 51 and winding wire 52 are connected. A holder or retainer for boughs 51 is provided on the end of the wire holder 46 as indicated at 53 and is adapted to receive the boughs from a beating device 54 to be later described. The wires 49 and 52 are fed from reels 54 and 55 journalled on the frame 10. The wire 52 which is used for winding is extended through a spring retaining device 56, Fig. 5, on the holder 46. This spring device serves to keep the winding wire 52 tight within its holder, and as it is wound over the boughs. This tightening device comprises a collar 58 which is fixed by an adjustable bolt 59 to the holder shaft or pipe 61 through which the central wire 48 extends. On the bolt 59 are washers 62 and 63 between which the wire 52 is extended. A spring 64 urges the washer 63 toward the washer 62. The spring 64 reacts against the collar 58.

On shaft 25 is a sprocket 65 which is connected by a chain 66 with the large sprocket 47 on the wire holder or spindle 46. On the frame portion 12 there is provided bearing brackets 66 in which is journalled a shaft 67 having a sprocket 68 thereon which is connected by a chain 69 with the small sprocket 48 on the wire holder or spindle 46. Accordingly shaft 67 can be driven from the wire holder or spindle 46.

The bough feeding device 54 comprises a long arm 71 which is pivoted at 72 to the frame portion 12 and is normally urged against a roll stop 73 on one of the legs 11 by a tension spring 74 connected to the lower end of the arm 71 and below the pivot connection 72 and anchored as indicated at 75 to an opposite leg 11 of the frame. The upper end of the arm 71 has cradle means 76 for receiving a group of boughs 77. A clamp 78 is pivoted on the cradle at 79 and is retained against the boughs 77 by a tension spring 81. The cradle 76 is pivotally connected on the end of the arm 71 at 82 and a long arm 83 depends therefrom. This arm 83, as the device 54 is swung toward the bough receiving portion 53 of the holder 42, to release the boughs 77, will serve to tilt the cradle 76 upon its pivot 82 in the manner as indicated in dotted lines in Fig. 1. This movement of the arm 83 is effected by the engagement of the arm with a stop 85 on the frame portion 13, Fig. 1. The clamp 78 will be released upon engagement with the bough receiving portion 53 whereby to automatically deliver the boughs 77 to the portion 53 through which the wires are extended.

The movement of the feed device 54 is automatic and is effected by a crank arm 87 connected to a shaft 88. This shaft has a sprocket 89 connected by a chain 91 with a small sprocket 92 on the shaft 67. The outer end of the crank arm 87 is connected by a link 94 and a swivel 95 to the arm 71. The arm 71 may come to rest on its inward movement against a stop 96. The driving relationship between the parts is such that for four turns of the bough receiving portion 53, there will be one turn of crank arm 87 and hence one delivery of the boughs 77 to the portion 53. The resulting product is a festoon of boughs.

It should now be apparent that there has been provided a festooning machine which is au-

tomatic, of simple construction, inexpensive to manufacture and easy to operate.

While various changes may be made in the detail construction, it shall be understood that such changes shall be within the spirit and scope of the present invention as defined by the appended claims.

I claim:

1. A festooning machine comprising a frame, 10 a wire holder and spindle journalled on the frame and comprising a central tube for containing a central wire, means externally of the central tube for containing a winding wire which is connected at one end to said central wire, a bough receiving portion on the spindle, a feed device for delivering boughs to the bough receiving portion on the spindle, drive mechanism for driving the spindle and the bough feed mechanism whereby 20 upon a given number of turns of the spindle the boughs will be delivered to the bough receiving portion, and the winding wire will be wound upon the boughs to bind said boughs to said central wire, said bough feeding device comprising 25 an arm pivoted on the frame and having a cradle connected to the upper end of the arm for receiving the boughs and adapted to be swung toward the bough receiving portion of the spindle, said drive mechanism including a crank and a 30 link extending between the end of the crank and the arm whereby to move the arm periodically from the bough receiving position to the bough receiving portion of the spindle.

2. A festooning machine as defined in claim 1 and said cradle being pivotally connected to the upper end of the arm, an arm depending from the cradle and adapted to cause the pivotal movement of the cradle upon the arm of the bough feeding device as the arm is moved toward the bough receiving portion of the spindle whereby to locate and cause the cradle to be drawn through the bough receiving portion of the spindle.

3. A festooning machine comprising a frame, 45 a wire holder and spindle journalled on the frame and comprising a central tube for containing a central wire, means externally of the central tube for containing a winding wire which is connected at one end to said central wire, a bough receiving portion on the spindle, a feed device for delivering boughs to the bough receiving portion on the spindle, drive mechanism for driving the spindle and the bough feed mechanism whereby upon a given number of turns 50 of the spindle the boughs will be delivered to the bough receiving portion and the winding wire will be wound upon the boughs to bind said boughs to said central wire, said driving mechanism including a pulley pinion and a wheel adapted 55 to be engaged by the pulley pinion to drive the wheel, means for mounting the wheel on the frame to be moved into and out of engagement with the pinion, a manually operative device connected with said adjustable means to effect 60 its operation at the will of the operator of the machine.

4. A festooning machine as defined in claim 3, and a brake surface adapted to be engaged by the wheel in its return position from engagement with the pinion whereby to bring the holder or spindle to an immediate stop.

5. A festooning machine comprising a frame, 70 a wire holder and spindle journalled on the frame and comprising a central tube for con-

taining a central wire, means externally of the central tube for containing a winding wire which is connected at one end to said central wire, a bough receiving portion on the spindle, a feed device for delivering boughs to the bough receiving portion on the spindle, drive mechanism for driving the spindle and the bough feed mechanism whereby upon a given number of turns of the spindle the boughs will be delivered to the bough receiving portion and the winding wire will be wound upon the boughs to bind said boughs to said central wire, said spindle having a wire retaining device for maintaining the wire which is

wound over the boughs in a tight condition when effecting the winding operation.
